F. M. SUTTON

INTERNAL COMBUSTION ENGINE

Filed June 29, 1921

UNITED STATES PATENT OFFICE.

FRANK M. SUTTON, OF MODESTO, CALIFORNIA.

INTERNAL-COMBUSTION ENGINE.

Application filed June 29, 1921. Serial No. 461,231.

To all whom it may concern:

Be it known that I, FRANK M. SUTTON, a citizen of the United States, residing at Modesto, in the county of Stanislaus and State of California, have invented new and useful Improvements in Internal-Combustion Engines, of which the following is a specification.

This invention relates to an internal combustion engine, and especially to an engine of the two-cycle type.

One of the objects of the present invention is to generally improve and simplify engines of the character described, and especially to provide an engine employing opposed cooperating pistons actuated by a common crank shaft so as to equalize bearing thrusts and to permit a balanced couple; further to provide an engine in which crank case compression may be entirely eliminated and in which charging and scavenging of the explosive mixture may be efficiently accomplished.

Another object of the invention is to provide a structure which permits compression and firing of the explosive mixture between the pistons and within one of the same; also a structure which permits the formation of ports for the delivery and discharge of the explosive mixture, thereby reducing the number of valves and connected mechanism required to a minimum.

Further objects will hereinafter appear.

The invention consists of the parts and the construction, combination and arrangement of parts as hereinafter more fully described and claimed, having reference to the accompanying drawings, in which—

Fig. 1 is a central, vertical, longitudinal section through the engine.

Fig. 2 is a similar section taken at right angles to Fig. 1.

Referring to the drawings in detail, A indicates a cylinder, B a crank case, 2 a crank shaft journaled in suitable bearings as indicated at 3, and 4 and 5 a pair of cooperating pistons; one disposed within the other and both connected with the crank shaft by means of the connecting rods indicated at 6 and 7.

Formed near the upper end of the cylinder is a chamber 8, and regulating the admission of gasses or air thereto is an inlet valve 9 which is lifted once during

each revolution of the crank shaft by means of a cam 10 and a pusher rod 11. Forming a communication between the chamber 8 and the upper end of the cylinder is a plurality of ports 12 and a single port 13, the function of which will hereinafter be described.

Formed near the lower end of the cylinder is a plurality of exhaust ports as indicated at 14, and forming a part of the cylinder is an annular exhaust discharge passage 15 with which the ports 14 communicate.

Formed in the upper end of the piston 4 is a plurality of ports 16, and formed near the lower end thereof is a similar set of ports 17. The ports 16 are adapted to communicate with the ports 12 and the chamber 8, and also with a chamber 18 in which is mounted a spark plug 19. The lower ports 17 are employed for scavenging purposes only and will therefore register with the exhaust ports 14 during the scavenging cycle as will hereinafter be described.

The piston 4 travels within the cylinder A. The interior of this piston is ground to form a cylinder chamber for the piston 5, and it may therefore be stated that the engine is divided into two separate chambers, one chamber 20 formed between the head of the piston 4 and the head of the cylinder indicated at 21, and a second chamber 22, which is formed interior of the piston 4 or between the pistons 4 and 5. The chamber 20 forms a primary suction and compression chamber for the gases or other mixture employed, while the chamber 22 forms a compression and firing chamber for the same gases. The cycle of operation will be as follows:

Opposed movement of the pistons 4 and 5 takes place due to the 180° offset formed by the cranks on the shaft. During downward movement of piston 4, an explosive charge is admitted through valve 9 and the chambers 8 and 20 are thus completely filled with the gas. During the upward stroke of piston 4, the mixture is compressed and is by-passed through the ports 12 and finally the ports 13 into the chamber 8 under fairly high compression. The moment however that piston 4 reaches its upper limit of movement, ports 16 will register with the ports 12 as shown in Fig. 1 and the

charge under compression held by the chamber 8 will thus be by-passed into the chamber 22 formed between the pistons 4 and 5. This charge is compressed during the next 5 movement of the two pistons which are in opposition to each other and when maximum compression is reached, register is made between the ports 16 and the chamber 18 containing the spark plug. A circuit is 10 simultaneously formed through the plug 14 and the charge is thus ignited. The firing and expansion of the mixture produces the driving force required and downward movement is imparted to the piston 5, while upward movement is transmitted to the piston 4. The charge is thus completely expanded and is exhausted the moment the ports 17 register with the ports 14 as shown 15 in Fig. 1. A new charge admitted to the 20 chambers 8 and 20 and compressed during the upward movement of the piston 4 is simultaneously admitted through the ports 12 and 16 and this charge is not only employed for the purpose of re-charging the 25 chamber 22, but also to assist complete removal or scavenging of the burned gases discharging through the ports 17, the cycle of operation being repeated once during each revolution, and a two-cycle operation 30 is thus obtained.

In actual practice it is obvious that the main cylinder may be cooled in any manner desired, either by water jacketing the 35 same or by providing cooling fins such as indicated at 25. To further assist cooling, a closed chamber has been formed in the upper part of the piston 4 as indicated at 26. This chamber may be partially filled with a fluid which will assist in conducting 40 or transferring the heat from the inner head.

From the foregoing it can be seen, first, that a two-cycle engine has been provided in which crank case compression is entirely 45 eliminated as the charge to be compressed and fired is admitted and by-passed by means of the piston 4 and the chambers 20 and 8 formed above the same; dilution of the lubricating oil contained in the crank 50 case, wear on the bearings and leakage losses are thus avoided; second, a uniform pressure is exerted on the crank shaft bearings during each revolution, and particularly during the firing cycle as the thrust of the 55 connecting rods and piston is in opposition to each other. This is of further importance as it permits, practically speaking, perfect balance or couple between the moving parts. Third, a structure is provided 60 which practically eliminates the use of valves as the ports formed in the cylinder and in the piston 4 permit automatic admission and discharge of the gases at proper timed intervals. In fact the only valve employed is that indicated at 9; this valve 65

being in reality nothing more or less than a check valve to prevent escape of gases from chamber 8 during the compressing cycle. Such a structure is of great importance as it materially reduces the cost of manufacture by eliminating a number of valves and the mechanism required to operate the same. Fourth, leakage losses of gases during compression and firing of the same will be reduced to a minimum in the present instance as compression takes place during half the time period required by a single piston engine. In other words where a charge is compressed rapidly, as in this instance, escape by leakage is reduced. Such leakage loss is furthermore prevented in the present instance due to the fact that the charge is compressed within the piston 4 and to escape it must either pass downwardly around the piston 5 or otherwise cut through the ports 16 and upwardly beyond the head of the piston 4. Such escape would however be of no importance as it would merely enter the chamber 20 where it would again be returned when the next charge is 75 by-passed to the chamber 22. In the same connection it may be stated that the crank shaft throw may be reduced to half that required by a single piston engine and as this is the case, it should be obvious that connecting rod throw and the vibrations produced thereby will be reduced to a minimum.

While I have in this instance described an engine operating on an explosive mixture admitted from a carburetor or other source of supply, it is obvious that the engine may operate on the Diesel principle, if desired, that is a pure charge of air would in that instance be admitted through the valve 9 and this charge when compressed would be by-passed to the chamber 22, where it would finally be compressed to an approximate pressure of 500 pounds. Such compression would heat the air to a sufficient temperature to permit the engine to operate on the Diesel principle. In that case the fuel injected would be received from the chamber 18, which would support a fuel atomizing nozzle as a substitute for the spark plug 19 shown. I therefore wish it understood that a two-cycle operation is permitted whether employing an explosive mixture or operating on the Diesel principle; further that while the general design is more or less specifically illustrated, I wish it understood that various changes in form and proportion may be resorted to within the scope of the appended claims, similarly that the materials and finish of the several parts employed may be such as the experience and judgment of the manufacturer may dictate or varying uses may demand.

Having thus described my invention,

what I claim and desire to secure by Letters Patent is—

A two-cycle engine comprising a cylinder, a normally closed intake chamber partially surrounding the upper end thereof and having aligned openings forming communication between the chamber and cylinder, one of said openings being elongated to extend upwardly to the cylinder head, a valve 10 for admitting fuel to the intake chamber, a hollow piston reciprocally mounted in the cylinder and forming a combined suction and compression chamber between the piston and cylinder head, the said piston 15 having ports at the upper end thereof, a second piston reciprocally mounted therein to form a combustion chamber between the two pistons, a crank shaft, and links connecting the said shaft and pistons in 20 opposed relation to each other, the upward stroke of the hollow piston adapted to compress the fuel charge in the combined

suction and pressure chamber, by-passing the same initially through the aligned openings and finally through the elongated 25 opening to the intake chamber and thence through the ports in the hollow piston to the combustion chamber, and an ignition device in the cylinder wall for firing the charge therein and an exhaust chamber 30 having ports between it and the chamber, said hollow piston having ports adjacent its lower end for registration with the ports of the exhaust chamber to effect discharge 35 of burnt gases, the lower ports of the hollow piston registering with said ports of the exhaust chamber simultaneously with registration of the upper ports of the hollow piston with the ports of the intake chamber so that upon recharging of the combustion 40 chamber the incoming gases assist in removal of the burnt gases into the exhaust chamber.

FRANK M. SUTTON.
